REGULATING DEVICE FOR REFRIGERATING APPARATUS

John Kirgan, Easton, Pa., assignor to Ingersoll-Rand Company, Jersey City, N. J., a corporation of New Jersey

Application March 25, 1936, Serial No. 70,749

12 Claims. (Cl. 62—152)

My invention relates to refrigerating apparatus, and especially to a regulating device to facilitate and ensure the continuous and normal operation of same.

5 An object of the invention is to provide novel means for limiting the minimum temperature to be imparted to a liquid refrigerant and thus prevent solidification or freezing thereof.

10 The invention is particularly adapted for use with a refrigerating system in which a liquid refrigerant is cooled in a high vacuum by vaporization of part thereof. In such a system the refrigerating effect depends on uninterrupted circulation and if freezing should occur operation would 15 be suspended.

Systems of the kind mentioned include an evaporator to receive the refrigerant, an evacuator for the removal of vapor therein and a condenser in which the vapor is liquefied. By means of a 20 suitable exhaust device the pressure in the condenser is made to sustain at a definite relation to the required low pressure in the evaporator to permit vaporization to proceed. If the pressure in the condenser becomes too great, the pressure 25 in the evaporator reaches too high a figure and vaporization is checked until pressure in the condenser again drops to a prescribed level. Hence by causing the pressure in the condenser to rise at a predetermined moment, further cooling can 30 be stopped and freezing of the system is averted.

Another object of the invention is to provide an apparatus by which the risk of freezing of the liquid refrigerant is eliminated through the operation of the exhausting unit for bringing about 35 the necessary low pressure in the condenser so that at the required moment the pressure in the condenser is caused to increase and the rate of vaporization is then diminished until normal conditions are again obtained.

40 An additional object of the invention is to provide a connection between the chilled liquid refrigerant leaving the evaporator and the power medium for actuating the exhaust device of the condenser such that the power medium is regulated in response to the falling temperature of 45 the refrigerant to give the desired result.

45 In its preferred form the invention comprises an evacuator of centrifugal design driven by a turbine, and the discharge of both machines is 50 transferred to condensers that are traversed by cooling water in series. To create a low pressure in the condenser for the compressor, an ejector such as a steam jet may be used, and the outlet for the chilled refrigerant has a thermostat coupled to a valve in the supply pipe for the ejector

5 to reduce the amount of power fluid therefor when the refrigerant is cooled too much. This reduction causes a rise in the pressure of the condenser coupled to the compressor which is immediately followed by a reduction in the output of the compressor and a reduction in the amount of vapor removed from the evaporator. The amount of vapor generated then decreases and the pressure and temperature are prevented from falling below the danger point.

10 Other objects and advantages of the invention will be fully apparent in the ensuing description and accompanying drawing; and while but one embodiment is shown I reserve the right to make changes in the shape, size and arrangement of 15 the various parts within the scope and principle of the invention.

On the drawing the figure is a side view partly 20 in section showing a construction according to this invention.

The numeral 1 indicates an enclosed vessel 25 called an evaporator which is exhausted of vapor created therein by means of an evacuator having the form of a centrifugal compressor 2. The liquid refrigerant to be cooled is introduced into 30 the evaporator through a header 3 having openings through which the refrigerant is expelled in the form of jets or sprays. The compressor 2 communicates with the inside of the evaporator through a port 4 and maintains a sufficient vacuum 35 in the evaporator to cause some of the refrigerant to be vaporized at once, and heat is thus taken out of the main body of the refrigerant so that the bulk of the refrigerant which remains liquid is chilled. It passes out through a 40 pipe 5 and is conducted to a place where the refrigerating effect is desired. After being warmed by absorbing heat thereat it returns to the evaporator through the header 3 and is cooled over. The compressor 2 is rotated by a turbine 6 that 45 is operated by steam supplied through a pipe 7 and this turbine may be coupled to the compressor through any suitable gearing shown at 8.

The compressor or blower delivers the vapor 50 that it takes out of the evaporator to a condenser 9, while the steam consumed in the turbine is discharged into a condenser 10 through an outlet flue 11. The condenser 9 receives water or other cooling medium through a pipe 12, and the water flows out of this condenser through a pipe 13 into 55 the other condenser 10 and leaves the other condenser by way of a pipe 14. The temperature of the condenser 10 and its internal pressure are therefore slightly higher than the temperature and pressure in the condenser 9.

To obtain the proper pressure in the condenser 9 below the atmosphere this condenser is connected to a steam ejector comprising a casing 15 which connects with the outlet pipe 11 of the 5 turbine. This casing communicates at its other end with the interior of the condenser 9 and it has an inside nozzle 16 connected to a steam pipe 17, the latter having a regulating valve 18 in a fitting 19 therein. So long as the valve 18 is 10 fully opened the pressure in the condenser 9 will be kept low enough to permit the compressor to continue evacuating vapor from the evaporator 1, but if the water passing out through the pipe 5 should ever become too cold the valve 18 will partly close by the action of a thermostat comprising 15 a bulb 20 in the pipe 5 and connected by a tube 21 to means to operate this valve. Both the bulb and the tube are filled with a thermally responsive liquid.

20 To enable this thermostatic element to move the valve the tube 21 is lead to an expansible casing 22 which is in operative relation with the outer end of the stem 23 of the valve 18. This stem has a head 24 on it and is encircled by a 25 spring 25 which normally tends to close the valve. The end of the casing 22 to which the tube 21 is attached is fixed, but the other end is movable and is engaged by the spring 25 between it and the fitting 19. So long as the bulb 20 does not 30 become too cool the pressure in the casing 22 will hold the valve 18 fully open, but this valve will move toward closed position when the thermally responsive fluid in the bulb and tube contracts. The condenser 10 for the turbine is pumped out 35 by any suitable appliance, not shown herein.

In operation the water temperature will at most 40 times be high enough to keep the valve 18 open against the spring 25, and the ejector 16 will then maintain a sufficiently low pressure in the condenser 9 to ensure satisfactory operation thereof. The water entering through the header 3 will be chilled, forced out through the conduit 5 to be warmed and then returned to be chilled again.

If, however, the temperature of the chilled water 45 passing out through the pipe 5 approaches the freezing point the contraction of the liquid in the bulb 20 and tube 21 will, at say 35° F., allow the spring 25 to compress the casing 22 and move the valve 18 toward closed position thereby cutting 50 down the steam supplied to the ejector 16. The capacity of the booster will be thus diminished and the temperature and pressure in the condenser 9 will increase and approach the temperature and pressure prevailing inside the other condenser 10. When this occurs the rate of 55 liquefaction of vapor in the condenser 9 will decrease due in part to the slower removal of gases by the ejector 16 and in part to the slower delivery of vapor by the compressor 2. The slower 60 delivery of vapor will in turn cause a decrease in the rate of vaporization and an increase in pressure in the evaporator 1.

The rate of vaporization in the evaporator will 65 also be greatly influenced by the variable compression characteristic of the compressor 2, for, when the back pressure on the compressor is increased the ratio of compression of the compressor will likewise increase. The increase of compression-ratio will be accompanied by a decrease 70 in capacity and this will in turn be manifested by a further increase of evaporator pressure and temperature and a further decrease in the rate of vaporization. Less heat will then be extracted from the water entering the evaporator and the 75 temperature of the chilled water will be prevented

from falling below the predetermined minimum. As soon as the temperature of the chilled water again exceeds the said minimum normal operation of ejector 16 will be resumed. Hence, it is seen that the decrease in the rate of vaporization 5 is a direct result of the decrease in the rate of liquefaction and the increase of pressure in condenser 9.

Other methods of decreasing the rate of liquefaction and increasing the pressure in the condenser, such as increasing the temperature of the incoming condenser cooling water, will be apparent to those skilled in the art. I, therefore, do not wish to be limited by the specific embodiment shown, but desire that the scope of the invention be determined by the claims hereinafter appended.

I claim:

1. The combination of a source of gaseous or vaporous fluid, a compressor for removing fluid 20 from the source, means for energizing the compressor, a condenser to which the compressor discharges, an ejector for exhausting the condenser, a condenser to which the ejector discharges, and means to vary the operation of the ejector in 25 accordance with variations of the temperature in said source whereby under certain temperature conditions the pressure in the first condenser approaches the pressure in the second condenser to limit the output of the compressor.

2. The combination of a source of gaseous or vaporous fluid, a compressor for removing fluid from the source, means for energizing the compressor, condenser means to which the compressor discharges, an evacuator for exhausting the 35 condenser, condenser means to which the evacuator discharges, means to pass cooling medium serially through the first and second said condenser means, the second said condenser means thereby operating under higher conditions of temperature and pressure than the first said condenser means, and means to vary the operation of the evacuator in accordance with variations of the temperature in said source to enable the pressure in the first said condenser means to approach 45 the pressure in the second said condenser means to limit the output of the compressor.

3. The combination of a source of gaseous or vaporous fluid, a centrifugal compressor for removing fluid from the source, a turbine for driving the compressor, a condenser to which the compressor discharges, a condenser to which the turbine discharges, a connection communicating between the condensers, means for impelling uncondensed gases from the first condenser through 50 said connection to the second condenser, and a device for regulating said means whereby under certain conditions the flow through said connection may be reversed to increase the pressure in the first condenser and thereby decrease the output 55 of the compressor.

4. The combination of a source of gaseous or vaporous fluid, a centrifugal compressor for removing fluid from the source, a turbine for driving the compressor, separate condensers for receiving the discharges of the compressor and turbine, a conduit connecting the condensers, means for impelling uncondensed gases from the compressor condenser through the conduit to the 60 turbine condenser, and a device acting in accordance with conditions at said source to control the operation of said means whereby under certain conditions the flow through said conduit may be reversed to augment the pressure in the com- 65

pressor condenser and thereby regulate the output of the compressor.

5. The method of compressing vapor which consists of removing vapor from its source, compressing the vapor, condensing the compressed vapor, exhausting uncondensed gases from the vapor as the vapor condenses, and varying the amount of uncondensed gases exhausted in accordance with variations of the temperature in the source of vapor to thereby vary the amount of vapor compressed and condensed.

6. The method of compressing vapor which consists in removing vapor from its source, compressing the vapor, subjecting the compressed vapor to condensing action, separating and removing uncondensed gases from the vapor as it condenses thereby to maintain low condensing pressure and a low ratio of compression, and varying the rate of removal of the uncondensed gases in response to the temperature at the source of vapor in order to vary the condensing pressure and the ratio of compression for maintaining such temperature above a certain minimum.

7. The combination of a vessel containing gas or vapor, a compressor to reduce the pressure in the vessel, means to energize the compressor, condenser means to which the compressor discharges, means for exhausting the condenser to reduce the pressure therein, means to supply power medium to the exhausting means, and a temperature responsive device actuated by the temperature in said source to vary the supply of power medium to the pump in accordance with variations of the temperature in said source whereby the operation of the pump is regulated to control the pressure in the condenser and the amount of fluid discharged by the compressor.

8. The combination of an enclosed vessel containing gas or vapor, a compressor to reduce the pressure in the vessel, a turbine for driving the compressor, a condenser to which the compressor discharges, a condenser to which the turbine discharges, an evacuator to reduce the pressure in the first said condenser and discharging into the second said condenser, means to supply power medium to the evacuator, and means acting in response to the temperature in the vessel to control the last said means and the operation of the evacuator and acting as the temperature falls in the vessel to cause the pressure in the first said condenser to approach the pressure in the second said condenser for controlling the output

of the compressor and the pressure and temperature in the vessel.

9. The combination of a source of gaseous or vaporous fluid, a compressor for removing fluid from the source, a condenser to which the compressor delivers, a device for exhausting said condenser, means for supplying power medium to the device, and a temperature responsive device actuated by the temperature in said source to vary the supply of power medium to the pump in accordance with variations in temperature of said source whereby the operation of the pump is regulated to control the pressure in the condenser and the amount of fluid discharged by the compressor.

10. The combination of a source of gaseous or vaporous fluid, a centrifugal compressor for evacuating said source, a condenser into which the compressor discharges, a steam ejector to exhaust the condenser and reduce its pressure, means to supply steam to the ejector, and means controlled by the temperature of the contents of said source and acting to regulate said steam supply to thereby determine the condenser pressure and the rate of discharge of the compressor.

11. The combination of a source of gaseous or vaporous fluid, a centrifugal compressor for evacuating said source, a power unit to operate the compressor, a condenser into which the compressor discharges, a second condenser, a pipe through which said unit discharges into the second condenser, an exhauster for the first condenser connected to said pipe, and means controlled by the contents of said source and acting to regulate the operation of said exhauster whereby under certain conditions of the source the pressure in the first condenser approaches the pressure in the second condenser to limit the output of the compressor.

12. The combination of a source of gaseous or vaporous fluid, a compressor for removing fluid from the source, means for energizing the compressor, a condenser to which the compressor discharges, means for exhausting the condenser, and temperature responsive means actuated by the temperature in said source to regulate and vary operation of the exhausting means in accordance with variations of the temperature in said source whereby the pressure in the condenser is regulated to control the output of the compressor.

JOHN KIRGAN.
